United States Patent Office

Des. 185,623
Patented July 7, 1959

185,623

SAFETY PAPER OR SIMILAR ARTICLE

Burton C. Berg, Dayton, Ohio, assignor to The Mead Corporation, Dayton, Ohio, a corporation of Ohio

Application December 2, 1958, Serial No. 53,615

Term of patent 14 years

(Cl. D59—6)

FIG-2

Fig. 1 is a plan view of a safety paper showing my new design; and

Fig. 2 is an enlarged fragmentary view thereof.

I claim:

The ornamental design for a safety paper or similar article, as shown.
